UNITED STATES PATENT OFFICE

2,409,815

MANUFACTURE OF OLEFINS

Clare Kenneth Viland, Martinez, and Herschel V. Hyde, Associated, Calif., assignors to Tide Water Associated Oil Company, San Francisco, Calif., a corporation of Delaware

Application January 25, 1943, Serial No. 473,456

8 Claims. (Cl. 260—683)

1

This invention relates to the manufacture of olefinic feed stock for alkylation and similar processes where a high concentration of olefins is desirable and has for a principal object the manufacturer of C₄ and C₅ fractions containing unusually high percentages of olefinic hydrocarbons.

Another object of the invention is to provide materials peculiarly adapted for pyrolytic conversion into desired olefins.

A further object is to reduce the quantity of normal pentane commonly present in stocks charged to alkylation or similar processes thereby increasing the plant capacity by elimination of a large proportion of those hydrocarbons not entering into the reaction.

Other objects will be apparent from the following description.

In the manufacture of modern aviation gasoline the alkylation process has become one of the most commonly used methods of obtaining gasoline fractions of high antiknock rating. As is well known, this process as most generally practiced comprises the formation of branch-chain paraffins chiefly in the boiling range of the octanes by the chemical combination of isobutane with butylenes. However, especially in cases where the supply of butylenes is inadequate to meet the demands for aviation gasoline, the alkylation process is also used to produce good antiknock gasoline components by reacting isobutane with amylanes.

The quantity of alkylate which may be produced in any given area, therefore, is limited by the available supply of isobutane, butylenes and amylanes as well as by the capacity of the alkylation plants. Present demands for aviation gasoline have resulted in the consumption of practically the entire supply of naturally occurring isobutane and numerous refiners have undertaken the installation of isomerization processes to augment the supply thereof. The chief source, if not the entire supply, of the required butylenes and amylanes is from the by-products of various pyrolytic processes, such as cracking and polymerization, which are primarily designed for the manufacture of hydrocarbons within the gasoline boiling range. Due to modern demands for butylenes and amylanes for alkylation purposes numerous pyrolytic plants are being operated principally for their production of these olefins.

As commonly practiced, butylenes for the alkylation process are obtained by isolating a C₄ cut from the products of the pyrolytic cracking and/or polymerization processes. Ordinarily this C₄ cut will contain from about 25% to 45% of butylenes,

2

the remainder being chiefly normal butane. As the normal butane cannot be readily fractionated from the butylenes without the use of extensive fractionating equipment, it is common practice to charge the entire C₄ cut to the alkylation process, along with the required amounts of isobutane. As the normal butane does not enter into the alkylation reaction, it passes through the plant unchanged and is fractionated from the products of the reaction. This procedure offers difficulties, however, when normal butane is present in large amounts. First, the throughput capacity of the alkylation reactor is reduced in proportion to the amount of the inert normal butane which is present. Second, in order to separate the normal butane from the products, a heavy load is placed on the fractionating equipment of the alkylation plant. Third, since the alkylation process requires the recirculation of large amounts of isobutane for the proper functioning of the process, the separation therefrom of the inert normal butane always results in the loss of substantial quantities of valuable isobutane into the normal butane due to imperfect fractionation. From the above it is seen that it is desirable to charge to the alkylation process a C₄ cut with as low a content of normal butane as possible.

Likewise, when amylanes are alkylated, the amylanes are obtained by isolating a C₅ cut from the products of the pyrolytic cracking and/or polymerization processes. Ordinarily this C₅ cut will contain from about 40% to 50% of amylanes, the remainder being chiefly pentanes. As the pentanes cannot be readily fractionated from the amylanes without the use of extensive fractionating equipment, it is common practice to charge the entire C₅ cut to the alkylation process, along with the required amounts of isobutane. As the normal pentane does not enter into the alkylation reaction, it passes through the plant unchanged and is fractionated from the products of the reaction. The presence of large amounts of the normal pentane offers difficulties similar to the presence of normal butane during butylene alkylation.

The present invention provides a method for producing larger amounts of amylanes from pyrolytic processes than are normally obtained therefrom, and provides a C₅ fraction containing from about 60% to 80% amylanes. In this way not only is the available supply of amylanes increased, but also a C₅ cut is provided which contains a substantially lower percentage of unreactive normal pentane. Simultaneously there is produced a C₄ cut which contains from about 40%

to 60% butylenes, which provides a more efficient C₄ fraction for butylene alkylation than is normally obtained from pyrolytic processes. The overall effect, therefore, is to furnish additional quantities of butylenes and amylenes and, coincidentally, to increase the capacities of the alkylation plants, whether alkylating amylenes or butylenes.

Briefly described, the invention comprises subjecting normal hexane to pyrolytic decomposition in the presence of substantial amounts of propylene and ethylene. When normal hexane is subjected to temperatures in the range of 1000° F. to 1300° F., it is decomposed into various olefinic and paraffinic hydrocarbons as a result of several more or less simultaneously occurring reactions of which the following appear to predominate:

- (1) C₆H₁₄=CH₄+C₅H₁₀
- (2) C₆H₁₄=CH₄+C₃H₆+C₂H₄
- (3) C₆H₁₄=C₂H₆+C₄H₈
- (4) C₆H₁₄=C₃H₈+C₃H₆

In accordance with the invention substantial quantities of propylene and ethylene are mixed with the normal hexane prior to carrying out the decomposition. The presence of the C₂ and especially the C₃ olefins tends to suppress (2) and (4) and thereby increases the amount of material undergoing reactions 1 and 3, resulting in the formation of larger amounts of amylenes and butylenes. Reaction 4 may be still further retarded by the addition of propane also to the mixture prior to pyrolysis. Likewise, if desired, ethane may also be added resulting in a suppression of Reaction 3 with a corresponding decrease in the production of butylenes and an increase in amylene production.

From the above it may be seen that, when normal hexane is subjected to pyrolysis to produce amylenes, the percentage of amylenes produced may be increased by increasing the concentration of any one of the C₂ or C₃ hydrocarbons present during the reaction. However, best results are obtained by increasing the concentration of all the C₂ and C₃ hydrocarbons, especially the C₂ and C₃ olefins.

Under the temperature conditions of the reaction, and especially in the temperature range of 1050° F. to 1150° F., there occur, simultaneously with the decomposition of the hexane, polymerizing reactions among the C₂ and C₃ hydrocarbons present resulting in the formation of additional quantities of amylenes and butylenes together with a large quantity of polymer gasoline of good anti-knock value. Isobutane, normal butane, isopentane, normal pentane, and, in minor proportions, polymer tars and other products are also formed. As stated above, the isobutane is a valuable constituent for the feed stock to the alkylation plant. Similarly, isopentane is useful as a feed stock for alkylation.

While the presence of any amount of C₂ and C₃ hydrocarbons will suppress Reactions 2 and 4 above to some extent, the effect increases with the amount of C₂ and C₃ hydrocarbons present. In order to obtain a substantial increase of Reaction 1 the C₂ and C₃ hydrocarbons should be present at least in equimolar proportion to the normal hexane, although a greater amount is to be preferred and a ratio of C₂ and C₃ hydrocarbons to normal hexane of 3:1 or greater is desired. Excellent results have been obtained using a molal ratio of about 7:1. In the C₂ and C₃ hydrocarbons charged as above, a ratio of 20% C₂ and 80%

C₃ hydrocarbons has been found to give good results.

In carrying out the process of the invention it may be convenient to use a conventional thermal polymerization plant. The accompanying drawing shows diagrammatically a typical thermal polymerization plant with modifications for carrying out the invention. In accordance with the invention normal hexane in line 1 and C₂ and C₃ hydrocarbons in line 2 are charged to pyrolytic zone 6 through line 5; the proportion of each being controlled by valves 3 and 4. In pyrolytic zone 6 the mixture is heated to the reaction temperature in coils 7 and 8 and the resulting products leave through line 9. Suitable pressure is maintained upon the mixture in the pyrolytic zone by means of valve 10. From line 9 the products enter fractionating zone 11 (which may advantageously comprise several fractionating columns arranged in accordance with well known principles of fractional distillation) wherein they are fractionally distilled to recover desired fractions, shown diagrammatically as leaving through lines 12, 13, 14, 15, 16, and 17 in the respective order of their boiling ranges. Through line 12 is withdrawn methane, and any hydrogen, formed during the reaction and sufficient ethylene (and ethane, if desired) to maintain the concentration of C₂ hydrocarbons withdrawn through line 13 within the desired range. This overhead gaseous fraction may be used as fuel. The remaining C₂ hydrocarbons together with the C₃ hydrocarbons are withdrawn through line 13 and recycled to the process through lines 18 and 19, being mixed with incoming fresh charge of C₂ and C₃ hydrocarbons in line 2 or 5. Through line 14 is withdrawn a C₄ cut which, under the operating conditions of the invention, will contain from about 40% to 60% of butylenes. Through line 15 is withdrawn the desired C₅ cut which, under the operating conditions of the invention, will contain from about 60% to 80% of amylenes. As previously stated, these C₄ and C₅ cuts may advantageously be used as olefinic feed for alkylation processes. Through line 16 is withdrawn a depentanized polymer gasoline while polymer tars leave the fractionating zone through line 17. If desired, normal hexane may be fractionated from the polymer gasoline in a second fractionating zone (not shown) and recycled to the process (through lines not shown) to be mixed with the fresh normal hexane in line 1 or 5.

Normal hexane for conducting the process of the invention may be produced in most refineries manufacturing aviation gasoline, being obtained as a by-product of relatively low value in the fractionation of straight run gasoline stocks, and other stocks, for the production of iso-hexane used as an ingredient in aviation gasoline. As is well known, the normal hexane thus obtained is generally not of 100% purity. According to common practice such a normal hexane fraction will include hydrocarbons having boiling points between 145° F. and 160° F., such as for example, 3-methyl pentane and 1,2 dimethyl cyclopentane in addition to normal hexane. Depending on the efficiency of the fractionation, a small amount of hydrocarbons having higher or lower boiling points may also be present, but generally not in excess of 5%.

While, for overall refinery efficiency, it is desirable to separate normal hexane of as high purity as possible, the process of the invention is adaptable to operate satisfactorily on normal hexane

stocks within the above range of purity. In the appended claims this range of purity is intended to come within the scope of the term "consisting essentially of normal hexane."

Following is an example of the process of the invention conducted in a conventional thermal polymerization plant. A fresh charge consisting of 600 barrels per day of propylene, 200 barrels per day of propane, and 1,000 barrels per day of normal hexane stock, together with 4,000 barrels per day of recycled C₃ hydrocarbons and 1,000 barrels per day of recycled C₂ hydrocarbons, was charged to the heating coil of the polymerization plant wherein the temperature was raised to 1125° F. The products from the heating coil were passed to the reaction section wherein the temperature was reduced to 1050° F. over a period of about 12 minutes. The products were then fractionally distilled into a gas fraction, a recycle fraction consisting of all the C₃ hydrocarbons together with a portion of the C₂ hydrocarbons formed, a C₄ cut containing all the C₄ hydrocarbons formed, a C₅ cut containing all the C₅ hydrocarbons formed, a depentanized polymer gasoline fraction, and a residual tar fraction. It was found that the C₄ fraction contained 50% of olefins and the C₅ fraction contained 65% of olefins. The following table shows results obtained compared to conventional operations where C₃ hydrocarbons are polymerized under similar operating conditions.

	Process according to invention	Conventional thermal polymerization
Fresh charge, bbl./day:		
Propylene	600	600
Propane	200	200
N. hexane stock (145°-160° F.)	1,000	
Total	1,800	800
Recycle stock, bbl./day:		
C ₂ hydrocarbons	1,000	1,000
C ₃ hydrocarbons	4,000	4,000
Total	5,000	5,000
Yields, bbl./day:		
Isobutane	30	25
Butylenes	125	50
N-butane	95	40
Isopentane	40	20
Amylenes	150	50
N-pentane	40	30
Other products	1,320	585
Total	1,800	800
Analysis of C ₄ fraction, per cent:		
Isobutane	12.0	21.7
Butylenes	50.0	43.5
N-butane	38.0	34.8
Total	100.0	100.0
Analysis of C ₅ fraction, per cent:		
Isopentane	17.4	20.0
Amylenes	65.2	50.0
N-pentane	17.4	30.0
Total	100.0	100.0

From the above table it is seen that, by introducing normal hexane into the charging stock of the polymerization plant in accordance with the invention, the yield of C₄ and C₅ hydrocarbons is greatly increased together with a substantial overall gain in the percentage of olefins therein.

Although a conventional thermal alkylation plant using normal operating conditions of time, temperature, and pressure is well adapted to the carrying out of the invention and although such operation is a preferred form of the invention, the invention in a broader sense is not limited to such operation. Any equipment may be used which is capable of maintaining the mixture of

normal hexane and C₂ and C₃ hydrocarbons at a cracking temperature for sufficient time that the desired amount of olefins is formed and various apparatus may suggest themselves to a skilled engineer.

Conventional polymerization furnaces are generally divided into two sections; the tubes or coils of the first section being subjected to a higher degree of heat than those of the second section. The process of the invention may be carried out in a single coil subjected to the necessary temperature, or a combination of heating coil and reaction chamber may be used if so desired.

Pressures employed in conventional polymerization plants are usually in the order of 300 to 500 lbs. per square inch at the outlet transfer line. While this pressure is preferable, for operating reasons, in the practice of the invention, other pressures may be used from atmospheric, or below, to one hundred or more atmospheres.

Fractionation is, in practically all cases, carried out in a series of fractionating columns under pressures sufficient to properly condense the necessary products and refluxes at the temperatures employed. The conditions of operation and design of such fractionating towers is well known to distillation engineers.

Likewise, the charge to the conventional polymerization plant (including both the feed and recycle stocks) is generally in the liquid phase. This is, however, merely an expedient and the charge of normal hexane and C₂ and C₃ hydrocarbons according to the invention may be either in the liquid or vapor phase as desired. Obviously, at the cracking temperatures involved, the materials undergoing the reactions will be above the critical temperature, and consequently, in the vapor phase.

We claim:

1. The process of producing a mixture of C₅ hydrocarbons containing a high proportion of amylenes which comprises: subjecting a hydrocarbon fraction consisting essentially of normal hexane to a temperature in the range of 1000° F. to 1300° F. while in the presence of added amounts of hydrocarbons from the group consisting of ethane, ethylene, propane, and propylene and in the substantial absence of other added hydrocarbons; fractionally distilling the resulting products; and separating therefrom a mixture of C₅ hydrocarbons; the molal ratio of normal hexane to C₂ and C₃ hydrocarbons subjected to the reaction being between about 1:1 and about 1:7.

2. The process according to claim 1 wherein the molal ratio of normal hexane to C₂ and C₃ hydrocarbons subjected to the reaction is not greater than 1:3.

3. The process according to claim 1 wherein the molal ratio of normal hexane to C₂ and C₃ hydrocarbons subjected to the reaction is about 1:7.

4. The process of producing a mixture of C₅ hydrocarbons containing a high proportion of amylenes, which comprises: subjecting a hydrocarbon fraction consisting essentially of normal hexane to a temperature in the range of about 1050° F. to about 1150° F. while in the presence of added amounts of hydrocarbons from the group consisting of ethane, ethylene, propane, and propylene and in the substantial absence of other added hydrocarbons; fractionally distilling the resulting products; and separating therefrom a mixture of C₅ hydrocarbons; the molal ratio of normal hexane to C₂ and C₃ hydrocarbons sub-

jected to the reaction being between about 1:1 and about 1:7.

5. The process of producing a mixture of C_5 hydrocarbons containing a high proportion of amylenes and a mixture of C_4 hydrocarbons containing a high proportion of butylenes, which comprises: subjecting a hydrocarbon fraction consisting essentially of normal hexane to a temperature in the range of 1000° F. to 1300° F. while in the presence of added amounts of hydrocarbons from the group consisting of ethylene, propane, and propylene and in the substantial absence of other added hydrocarbons; fractionally distilling the resulting products; and separating therefrom a mixture of C_5 hydrocarbons and a mixture of C_4 hydrocarbons; the molal ratio of normal hexane to C_2 and C_3 hydrocarbons subjected to the reaction being between about 1:1 and about 1:7.

6. The process of producing a mixture of C_5 hydrocarbons containing a high proportion of amylenes which comprises: flowing a stream of hydrocarbons consisting essentially of normal hexane through a conduit, simultaneously flowing a stream consisting of hydrocarbons lighter than C_4 hydrocarbons and heavier than methane through said conduit in admixture with said normal hexane while in the substantial absence of other added hydrocarbons, heating the mixture in conduit to a temperature between 1000° F. and 1300° F., maintaining the mixture at said temperature for sufficient time that a portion of the

normal hexane is cracked forming amylenes, reducing the temperature of the resulting products, fractionally distilling the resulting products and separating therefrom a fraction composed mainly of the C_5 hydrocarbons present in said products; the molal ratio of normal hexane to C_2 and C_3 hydrocarbons subjected to the reaction being between about 1:1 and about 1:7.

7. A method comprising thermally cracking at a temperature in the order of 1000° F. to 1300° F. a mixture of normal hexane, C_2 hydrocarbons and C_3 hydrocarbons while in the substantial absence of other added hydrocarbons and fractionally distilling a C_5 fraction from the resulting products; the molal ratio of normal hexane to C_2 and C_3 hydrocarbons subjected to the reaction being between about 1:1 and about 1:7.

8. A process of producing C_5 hydrocarbons which comprises: heating normal hexane to a cracking temperature in the order of 1000° F. to 1300° F. while in the presence of an added quantity of C_2 and C_3 hydrocarbons and in the substantial absence of other added hydrocarbons, and maintaining such temperature for a period of time sufficient to form a C_5 fraction containing in the order of from 60% to 80% of olefins; the molal ratio of normal hexane to C_2 and C_3 hydrocarbons subjected to the reaction being between about 1:1 and about 1:7.
